UNITED STATES PATENT OFFICE.

SAMUEL ROBIN, OF CHICAGO, ILLINOIS.

DESIGN FOR AN ADVERTISING-FLAG.

No. 38,694.

Specification for Design.

Patented July 23, 1907.

Application filed June 14, 1907. Serial No. 379,096. Term of patent 3½ years.

To all whom it may concern:

Be it known that I, SAMUEL ROBIN, a citizen of the United States, residing at Chicago, in the county of Cook and State of Illinois, have invented a new, original, and ornamental design for Advertising-Flag, of which the following is a specification, reference being had to the accompanying drawing, forming part thereof, in which is shown in elevation my design for an advertising-flag.

I claim as my invention

The ornamental design for an advertising flag, shown in the accompanying drawing.

SAMUEL ROBIN.
